Patented Dec. 26, 1916.

UNITED STATES PATENT OFFICE

EUGENE J. MOYNIHAN, OF SAN FRANCISCO, CALIFORNIA.

STEAM-SHOVEL.

1,210,194.

Specification of Letters Patent. Patented Dec. 26, 1916.

Application filed April 12, 1916. Serial No. 90,624.

To all whom it may concern:

Be it known that I, EUGENE J. MOYNIHAN, a citizen of the United States, residing at San Francisco, in the county of San Francisco and State of California, have invented new and useful Improvements in Steam-Shovels, of which the following is a specification.

The present invention relates to improvements in steam shovels and the like.

It is a matter of common experience with operators of steam shovels that much time is wasted in operating the dipper to pick up loose material lying on the ground at the same height as, or lower than, the track on which the steam shovel is movable. The operator has, with the present construction of steam shovel, to draw the dipper back over the loose material and then, lowering the dipper, advance it over said material several times in order to cause the material to enter the dipper.

My invention has for its object to avoid the necessity of operating the dipper in this manner and thereby to effect a great saving of time.

I have herein shown my improvement as applied to a Bucyrus steam shovel, but it is to be well understood that with suitable obvious changes, it may equally well be applied to any form of steam shovel.

In the accompanying drawing, Figure 1 is a side elevation of a portion of a steam shovel showing my invention applied thereto; Fig. 2 is a plan view of a portion thereof, especially showing my invention; Fig. 3 is an enlarged sectional view on the line 3-3 of Fig. 2.

Referring to the drawing, 1 indicates the frame and 2 the front truck of a steam shovel, to which my invention is shown as applied.

3 indicates the boom and 4 the dipper handle, pivoted upon a shipper shaft 6, having thereon shipper shaft gear wheels 7.

8 indicates the dipper pivotally carried upon the end of the dipper handle, and 9 a hoisting chain or cable, passing around pulleys 11, 12, and wound upon a hoisting drum 13 having a hoisting gear wheel 14.

All of the above is old and in common use and forms no part of my present invention.

Bolted, as shown at 16, to the car body are uprights 17, 18, carrying boxes 19, 20 for a rotary shaft 21. Said shaft has secured thereon a gear wheel 22 which con-

tinually meshes with the hoisting gear wheel 14. Said gear wheel 22 is formed on one side with a rib 23 coaxial with the shaft 21 and angular in cross section, to make frictional engagement with the sides of an angular groove 24 formed in the side of a flange 26 of a winding drum 27 loose on said shaft 21. Said winding drum 27 is movable longitudinally on said shaft toward said gear wheel 22 by means of a lever 25 on a shaft 30 on which is an arm 15, shown in dotted lines in Fig. 1, connected to one end of a link 35 connected to a lever 28 secured to the outer end of a threaded rod 29 screwed into a block 31 in line with the center of the shaft 21, said block being secured, as shown at 32, to the upright 18. Extending in a central hole of the shaft 21 is a pin 33, which, at the outer end, is engaged by the forward end of the threaded rod, while its inner end engages a slide bar 34 extending transversely through diametrically opposite slots 36 in the hollow shaft and retained in such position by means of setters 37 through 80 its opposite ends. This slide bar engages the face of a hub 38 formed at the end of the drum 27 remote from the gear wheel. By turning the lever 28 in the proper direction, the grooved flange 26 of the drum 27 is forced against the annular rib 23 on the face of the gear wheel, and by the frictional engagement of said flange and rib the drum is caused to rotate with the gear wheel. The drum 27 can be arrested immediately by the operation of a foot brake 40.

Around the drum is wound a cable 39 which extends around guide pulleys 41 and 42, and then over a pulley 43, the outer end of said cable being attached to a snap hook 91 which is attached to a loop 45 which is attached to a cable 46 which extends around a pulley 47 suspended from the dipper handle and is then fastened with a U-shaped bolt 48 to the bottom of the door 49 of the dipper. There is also attached to the loop 45 one end of a coiled spring 51 surrounding the cable 46, the other end of said coiled spring being attached, as shown at 47, to a stationary point on the dipper handle. The object of the coiled spring 51 is to take up the slack when the cable 39 is unwound from the drum. The pulley 43 is formed like a snatch block, so that the cable 39 can be withdrawn therefrom and extend direct between the pulley 42 and the spring 51, for heavy work.

There is secured to the end of the dipper handle a guideway 52 for a spring-actuated latch 53, the forward end of said latch being adapted to be engaged by a wedge-shaped projection 54 on the door of the dipper when said door swings open and to be pressed back against the spring until said projection has passed the end of the latch, whereupon the latch springs forward under the pressure of said spring and holds said dipper door in the open position. The outer end of said latch 53 is attached by a chain 56 to the dumping lever 57 which is part of the present machine.

15 The following is the operation of my invention:—The dipper is raised by means of the main hoisting drum 13 winding up the hoisting line or chain 9. After the dipper door has been opened by pulling the dumping lever and releasing the latch bar, in the usual manner for the purpose of dumping the material in the dipper, friction is thrown off the main hoisting drum which is then only controlled by a foot brake, and the dipper descends with the door open. As it descends the drum 27 winds up the cable 39, this drum being in frictional engagement with the gear wheel 22 and therefore driven by the engine. The dipper thus descends to the ground with the door wide open. The operator then causes the dipper to move on the ground in a backward direction by suitably operating the boom engine, and drawing back the cable attached to the bottom of the door by means of the main engine, at the same time rotating the drum 27, and winding up the cable 39, so as to maintain said door open, and it may be observed that the tension on the cable 39, after pulling the door wide open, assists in drawing back the dipper. By this backward movement the greater part of the loose material is caused to enter the dipper. In prior devices it has been necessary, in order to secure the entrance of this loose material into the dipper, to cause the dipper to travel backward above the material and then forward again in a lower position through the material, a great many

times, an operation which entailed considerable loss of time. By my invention all this loose material can be gathered into the dipper by a single backward movement. By pulling the trip line 61, the door will now be released from the latch 53, and can be lowered by means of the cable 39 controlled by the drum 27. The usual bolt 57 upon the back of the door drops into the hole 58 therefor.

I claim:

1. In combination with the dipper of an apparatus of the character described having a door for closing the bottom of the dipper, and unitary means operated from the frame work of the apparatus whereby the door of the dipper may be positively held open when the dipper is close to the ground, and whereby the bucket may be drawn rearwardly.

2. In combination with the dipper of an apparatus of the character described having a door for closing the bottom of the dipper, means operated from the frame work of the apparatus whereby the door of the dipper may be positively held open when the dipper is close to the ground and a spring-actuated latch adapted to be engaged by the door when swinging wide open to hold the door in the open position.

3. In combination with the dipper of an apparatus of the character described having a door for closing the bottom of the dipper, means operated from the frame work of the apparatus whereby the door of the dipper may be positively held open when the dipper is close to the ground, means automatically engaged by the door when swinging wide open to hold the door in the open position, and means for releasing said automatically engaged means.

In testimony whereof I have hereunto set my hand in the presence of two subscribers:

EUGENE J. MOYNIHAN.
